UNITED STATES PATENT OFFICE

HAROLD B. DONLEY, OF COLUMBUS, OHIO, ASSIGNOR TO COLUMBUS AUTO BRASS COMPANY, OF COLUMBUS, OHIO, A CORPORATION OF OHIO

LAMP CONSTRUCTION

Application filed September 14, 1931. Serial No. 562,758.

This invention relates to lamp constructions more particularly directed to that type of lamp used for ornamental purposes primarily in connection with motor vehicles such as ambulances, hearses, delivery trucks, or other vehicles of like nature.

An object of the present invention is to provide a lamp of this character which will have an ornamental and pleasing appearance and which, when in use or lighted, will give a crystal or star-like effect and add to the dignity and character of the vehicle upon which it is carried.

Another object of the invention lies in the provision of a lamp of this character where in an extremely simple construction is present, rendering the same particularly desirable from a manufacturing and assembly standpoint, and which when in use may be readily serviced.

With these and other objects in view, which will appear as the description proceeds, the invention consists in the novel features of construction, combinations of elements and arrangements of parts hereinafter to be more fully described and pointed out in the appended claim.

In the accompanying drawing:

Figure 1 is a front elevation of the lamp comprising the present invention,

Figure 2 is a side elevation thereof,

Figure 3 is an enlarged vertical sectional view taken through the lamp as indicated by the line 3-3 of Figure 1, and

Figure 4 is a horizontal sectional view taken on the line 4-4 of Figure 2.

Referring more particularly to the drawing, the numeral 1 designates the lamp in its entirety which is formed to comprise a vertically arranged substantially cylindrical housing 2 which has its upper and lower ends closed by means of end members 3 and 4 formed and shaped to give an ornamental appearance to the lamp. To further ornament the lamp the cylindrical side wall of the housing 2 at the front and sides thereof is provided with a plurality of light openings in the form of cut-outs or slots 5 which extend substantially the full height of the housing and are separated by webs 6. These webs

have their outer faces ornamented by forming therein longitudinal corrugations which enhance the beauty of the lamp as well as strengthen the webs. Attached to the back of the housing such as by rivets or the like 55 is an anchoring casting 8 which is adapted to be received within a substantially U-shaped bracket 9 attached to a supporting member 10 which may be the roof pillar of a vehicle body. The casting is held in place within the bracket 9 by a bolt member 11 passing vertically through aligned openings formed in said bracket and casting and which bolt is retained in place by the threaded lock nut 12. As the casting 8 is positioned snugly 60 within the bracket 9, the lamp will be secured in place therein in a rigid manner relative to its supporting structure.

Arranged within the housing 2 is a cylindrical lens or transparent member 13 which is of such cross-sectional area as to snugly engage with the inner wall surface of the housing, and which is of such length as to completely cover the elongated slots or openings 5. The lens member 13, which is in the shape 70 of a glass tube having open ends, is held in place within the housing between the lateral shoulders 14 formed upon upper and lower concaved reflecting members 15 and 16 respectively. The lower reflector member 16 rests 75 upon a conically shaped coil spring 17 which has its lower end engaging the restricted lower tapered end of the end member 4 and its upper end engaging a shoulder 18 formed upon the reflector member 16. By the provision of the spring 17 the lens member 13 is 80 resiliently supported to prevent breakage thereof and to accommodate for certain irregularities as to the length of the lens.

Arranged in the longitudinal axis of the 90 lamp and carried by the upper reflector member 15 is a bulb mounting 19 having the usual bayonet slot connection 20 by which the incandescent lamp 21 is detachably connected. Leading to the lamp is a pair of electric conductors 22 which enter the housing through a sleeve 23 formed in the upper end member 3 of the lamp. The conductors 22 may pass to any convenient point on the lighting circuit of the vehicle and the incandescent bulb 100

21 may be supplied with current from the usual battery of the vehicle. Arranged immediately to the rear of the lens and positioned between the lateral and the rear portion 5 of the housing is a convexly shaped reflecting member 24 which extends the full height of the housing 2 and which may be attached thereto by soldering the same in place or in any other manner well known in 10 the art. This reflecting member, which is provided with a highly polished inner surface built together with the polished inner surfaces of the members 15 and 16, reflects light rays from the lamp bulb 21 outwardly and 15 forwardly through the lens covering slots or cut-outs 5. This reflected light may be divided into separate beams by the webs 6 thereby producing a multiplicity of light rays which together with a multiplicity of reflecting surfaces will give what may be called a 20 crystal-like effect which lends a distinctive appearance to the vehicle.

To hold the lens member 13 and other various parts in their assembled relationship, 25 the upper edge of the housing 2 is provided with bayonet slots 25 for cooperation with pins 26 carried by the lower cylindrical edge 27 of the upper end member 3. By means of this pin and bayonet slot connection the end member 3 will be held in a locked position upon the upper end of the lamp housing and will also serve to exert a downward pressure upon the lens 13 against the action of the spring 17, which spring pressure will prevent 30 accidental displacement of the member 3 relative to the lamp housing. A gasket 28 may be positioned between the upper of the flanges 14 and the end member 3, which serves as additional cushioning means for the support of the lens and prevents rattle and 35 looseness of the parts.

From the foregoing it will be seen that a construction has been provided which is extremely novel and wherein the parts are so 40 arranged as to be readily assembled for service. The lamp when in use will give an unusual lighting effect due to the formation of the lamp housing and the provision of the vertically arranged, separated slots or light 45 windows therein. By the arrangement of these light openings together with the concave upper and lower reflecting members, which are visible through said windows, the light 50 from the lamp will be reflected and split up into a multiplicity of rays producing a light of highly unusual character. The lamp may 55 be readily serviced, for the replacement of a bulb therein or for the cleaning of the lens, by the detachment of the upper end member 60 3. The conical ornamental end members together with the longitudinal ribs or corrugations give the lamp a design which has a 65 pleasing appearance.

What is claimed is:

65 In a lamp of the character described, a ver-

tically arranged cylindrical housing having spaced longitudinally extending slots formed therein which extend over the forward and side portions of said housing, the unslotted portion of said housing carrying a reflecting surface, upper and lower end members of ornamental form closing the ends of said housing, a cylindrical lens within said housing covering said slots, inwardly directed concave reflecting members positioned in the ends of said lens, an incandescent lamp bulb carried by the upper of said reflecting members and arranged inwardly with respect thereto, a spring member arranged between the lower of said reflectors and the lower of said end 70 members for effecting the resilient support of said lens and bulb mounting structure, a compressible gasket between the upper of said reflectors and the upper of said end members, and a bayonet slot connection between the 75 upper end of the housing and the upper of said end members.

In testimony whereof I affix my signature.

HAROLD B. DONLEY.
